UNITED STATES PATENT OFFICE.

FREDERICK W. BECKER, OF NEW YORK, N. Y.

DESIGN FOR A CHIN-PLATE FOR VIOLINS.

46,490.

Specification for Design.

Patented Oct. 6, 1914.

Application filed May 2, 1914. Serial No. 836,081. Term of patent 3½ years.

To all whom it may concern:

Be it known that I, FREDERICK W. BECKER, a citizen of the United States, residing at New York city, in the county of Bronx and State of New York, have invented a new, original, and ornamental Design for Chin-Plates for Violins, of which the following is a specification, reference being had to the accompanying drawing, forming part thereof.

Figure 1 is a front elevation, and Fig. 2 is a side elevation of a chin plate embodying my new design.

Referring in detail to the drawings, the chin plate 10 is formed with two downwardly projecting spaced slender feet 11 of curved cross section, which rest upon the sound box of the instrument.

The essential feature of the invention consists in the formation of the feet 11, projecting downwardly from the chin plate 10, these feet being slender, giving an appearance to the chin plate of lightness and constituting a pleasing outline.

I claim:

The ornamental design for a chin plate for violins consisting of a plate and the downwardly projecting slender spaced feet, substantially as shown and described.

FREDERICK W. BECKER.

Witnesses:

MINNIE S. MILLER,
Wm. I. COHEN.
